(57) **CLAIM**

The ornamental design for an air conditioning apparatus as shown and described.

DESCRIPTION

1. Air conditioning apparatus

1.1 : Perspective

1.2 : Perspective

1.3 : Perspective

1.4 : Front

1.5 : Top

1.6 : Bottom

1.7 : Left

1.8 : Right

Reproductions 1.1 to 1.8 show the design of an air conditioning apparatus for indoor installation, the characteristic features of the design residing in the particular shape of the body and vents of the air conditioning apparatus; reproductions 1.4-1.8 are truly isometric views of the design, while reproductions 1.1 to 1.3 show the design in perspective.

1 Claim, 8 Drawing Sheets
